Filed June 17, 1958, Ser. No. 742,541
7 Claims. (Cl. 214—1)

This invention relates to hand trucks or carriers for outboard marine engines, and more particularly to hand-operated carriers intended to facilitate the transfer of an outboard engine from a vehicle to a boat, and vice versa.

Various types of outboard engine carriers and transfer devices have been proposed and constructed in the past for the purpose of facilitating the handling of outboard marine engines. While these prior devices have in general to a greater or lesser extent made easier the task of transporting and handling outboard engines, there was still required a certain amount of heavy lifting and exertion, and with the advent of the larger and more powerful outboard engines this became a serious problem.

With prior carrier devices it was often necessary to do appreciable direct lifting of the outboard engine without benefit of any labor-saving means. Moreover, where the engine was to be placed in a location on the vehicle which was not readily accessible the task became increasingly difficult due not only to the appreciable weight of the engine and its size and bulk, but also due to the cramped spaced accommodations of the vehicle body, trunk compartment or the like.

The above disadvantages and drawbacks of prior outboard engine carrier devices are obviated by the present invention, and one object of the invention is to provide a novel and improved outboard engine carrier which virtually eliminates the necessity for direct lifting of the engine, even when the latter is to be placed on an elevated platform, car body, trunk compartment or the like.

A further object of the invention is to provide an improved outboard engine carrier as above set forth, which enables various tilting and swinging operations to be easily carried out in manipulating the engine from one position to another desired position.

Still another object of the invention is to provide an improved outboard engine carrier as above characterized, wherein both horizontal and vertical, pivotal or swinging movement of the engine, as well as elevation of the same, may be easily and conveniently carried out to effect the desired transfer from one location to another.

An important feature of the invention resides in the provision of a novel and improved outboard engine carrier which is constituted of two separate and cooperable conveyance means, shown in the illustrated embodiments of the invention as a hand cart and a dolly, said means together cooperating to effect in a unique manner an easy and convenient handling and transportation of the engine.

Another object of the present invention is to provide a novel outboard engine carrier as above defined, which is safe and reliable in its operation at all times, thereby reducing to a minimum the likelihood of injury to personnel operating the carrier.

A still further object of the invention is to provide an improved engine carrier means which is so effective in the saving of labor that it may be readily operated by women and children.

2

A further object of the invention is to provide an improved engine carrier in accordance with the foregoing, which may be readily utilized to handle all types of outboard marine motors, both large and small, with the greatest ease and facility.

Another and important object of the invention is to provide an improved engine handling device of the type outlined, by which an outboard marine engine may be readily and conveniently taken from a position lying on the ground, transported over the ground to another desired location, and there easily raised and shifted or placed in an available space in or on a vehicle.

A further feature of the invention resides in the provision of an improved engine carrier which has all of the above advantages and is nevertheless extremely simple in its construction, sturdy, long-lived, and economical to fabricate.

Yet another feature of the invention resides in the provision of an outboard engine carrier in accordance with the foregoing, which may be easily and quickly dismantled and stored in a relatively small space.

Other features and advantages will hereinafter appear.

In the drawings accompanying this specification, similar characters of reference are used to designate like components throughout the several views, in which:

FIGURE 1 is a side elevational view of the present improved outboard engine carrier, as provided by the invention.

FIG. 2 is a front elevational view of the carrier shown in FIG. 1.

FIG. 3 is a horizontal sectional view taken on the line 3—3 of FIG. 2.

FIG. 4 is a perspective view of the hand cart portion of the carrier shown in FIGS. 1 and 2.

FIG. 5 is a perspective exploded view of the dolly portion of the engine carrier of FIGS. 1 and 2.

FIG. 6 is a fragmentary perspective view showing a modified form of engine mounting support, adaptable for use with the hand cart shown in FIG. 4.

FIG. 7 is a fragmentary sectional view taken on the line 7—7 of FIG. 6.

Referring first to FIGS. 1—4, the engine carrier and handling device shown therein is seen to comprise two separate carrier structures which are intended to have a cooperable relationship and to be mounted one on the other, said structures however being completely separable so that one may be used independently of the other. These two separate structures comprise a dolly assemblage shown separately in FIG. 5 and indicated by the numeral 10, and a hand cart assemblage shown separately in FIG. 4 and indicated by the numeral 12.

In FIGS. 1 and 2 the hand cart assemblage 12 is illustrated as mounted on the dolly assemblage 10 so as to be carried thereby. Also illustrated in FIG. 1, in broken outlines is an outboard marine engine occupying two different positions; the hand cart portion 12 is additionally shown in this figure in a broken outline position, corresponding to one of the indicated positions of the outboard engine. Further, in FIG. 1 the hand cart portion 12 is illustrated in a third position by another broken outline, to illustrate the possible movements which the hand cart may have while supported on the dolly 10.

Referring now particularly to FIG. 5, the dolly 10 may be advantageously constituted as a T-shaped frame 13 comprising a stem or center bar 14 having at one

end a cross-bar 15 which is rigidly secured to the center bar.

At its ends the cross bar 15 rotatably carries wheels 16, which are preferably of the rubber-tired kind having peripheral surfaces of appreciable area whereby the 5 wheels will not readily sink into soft earth or sand.

The center bar or stem 14 at its free end is provided with a caster 18 which may be of any usual type, preferably provided with a relatively large wheel 19 and with an antifriction mounting means 20 by which the 10 caster may easily swing in various directions. Preferably the wheel 19 of the caster also has a fairly expansive peripheral surface, to enable it to traverse soft earth and sand without appreciably digging into the same.

The dolly 10 also comprises an upright post 21 which 15 may be constituted of two separable parts, an upper part 22 of appreciable length and a lower part 23 of much shorter length. A separable rotary connection is provided between the parts 22 and 23 of the upright 21, and in its simplest form this separable connection comprises a sturdy pin or bar 25, which may be rigidly carried by the upper part 22 of the post and which may 20 slidably fit into and have a bearing in the lower part 23.

To position the parts 22 and 23 axially with respect to each other when the upper part is mounted on the lower part, cooperable shoulders are provided on the said parts, said shoulders being indicated at 27 and 28 and parts, said shoulders being indicated at 27 and 28 and constituting the adjoining, abutting ends of the parts 22 and 23.

The upright post 21 may be advantageously formed of 30 heavy steel tubing, or of steel pipe or the like, and similar structural forms may be used for the cross-bar 15 and the center bar or stem 14. Also, the members 14, 15 and 25 23 may be rigidly secured together by a suitable welding procedure.

Considering now the hand cart construction shown in FIG. 4, this may comprise a pair of tubular side frame members 30 secured together intermediate their ends by a tubular cross-bar 31. The side frame members 30 have angularly bent upper extremities 32 provided with suitable 40 handle means 33, as is usual in hand carts.

At their lower extremities the side frame members 30 carry a shaft or spindle 35 which is preferably rigidly secured to the side members. Said members may have 45 their lower ends flattened and apertured to receive the shaft 35, as indicated.

At the ends of the shaft 35 wheels 37 are rotatably mounted, said wheels being preferably of the rubber-tired type and having peripheral surfaces of relatively great area whereby the wheels will not appreciably sink in soft earth or sand as the hand cart is being used to traverse such terrain.

In accordance with the present invention, on the upper portion of the side members 30 of the hand cart 12 we provide a stout cross-bar 39, which is preferably of 55 a rectangular cross-section and which may be advantageously constituted of wood framing, as for example a length of 2 by 4 fir. The cross-bar 39 is adapted to have being indicated in two different positions by broken outlines in FIG. 1. The marine engine therein is designated by the numeral 42.

As is well understood in connection with such marine engines, these are usually provided with sturdy mounting brackets having thumb screws or the like, by which the engines are intended to be supported on a cross member of appreciable thickness.

As seen in FIG. 4, we provide on the cross bar 39 a pair of end brackets 44, which are preferably formed of sheet metal, for the purpose of securely attaching the cross bar or member 39 to the side members 30 of the hand cart structure 12. The brackets 44 may be advantageously constructed to have circular or tubular portions 45 adapted to extend around the tubular members 30, and such portions may be secured to the side members by 70

means of suitable bolts 46. The tubular portions 45 may have several sets of holes, each set being adapted to accommodate a bolt 46 whereby the brackets may be positioned either higher or lower on the side members.

The brackets 44 have flat web portions 48, which are preferably of double thickness as shown, and have angularly bent or offset flanges 49, the portions 48 and 49 being adapted to engage the ends and front adjoining surfaces of the stout cross-bar 39, as shown. Any suitable means may be provided for securing the cross bar 39 to the brackets 44, such as screws, through bolts and the like.

In accordance with the present invention the upright post 21 of the dolly structure 10, by means of its rotary connection to the part 23, is adapted to constitute a rotary mounting means for the hand cart 12 whereby the latter may be mounted on the dolly and swung to various positions about a substantially vertical or upright axis. Also, in accordance with the present invention, we provide cooperable shoulder means on the dolly 10 and hand cart 12, constituting a separable connection by which the hand cart may be readily mounted on and carried by the dolly and also separated from the latter when this should be desired for the purpose of handling or transporting the outboard engine attached to the hand cart. The said separable connection comprising the shoulder means may advantageously include the cross bar 31 of the hand cart structure 12, as seen in FIGS. 1, 2 and 4. Such separable connection also comprises a shoulder means attached to the upper extremity of the upright post 21. For such shoulder means we provide a horizontally extending structural steel member in the form of a length of angle iron 52 which is disposed with the flanges thereof extending upward and outward at an angle. The angle iron 52 is rigidly attached at a point midway of its ends to the upper extremity of the post 21. Such attachment may for example be advantageously effected by means of a suitable welding procedure.

The horizontally disposed section of angle iron 52 is constituted to act as a nest or support for the cross bar 31 of the hand cart 12. This may be readily seen from an inspection of FIGS. 1 and 2 wherein the cross member 31 is shown as resting in the open portion of the angle iron 52. Preferably the length of the angle iron 52 is slightly less than that of the cross bar 31, thereby to enable the hand cart 12 to be readily mounted on and removed from the dolly 10.

In conjunction with the said separable connection comprising the cooperable shoulder means, we further provide a connection between the lower portion of the hand cart 12 and the dolly 10. Such connection may advantageously involve the spindle or shaft 35, and as seen in FIGS. 2 and 4 the center portion of such shaft is provided with an upwardly offset portion or bend 54 which is adapted to engage and receive the center bar or stem 14 of the dolly. We also provide a spring clip 56 on the center bar 14, for engagement with the bend 54 of the shaft 35 to frictionally releasably hold the said shaft to the center bar. Such arrangement may be clearly seen in FIG. 1, for example.

With the above construction it will now be understood that, as indicated by the arrows shown in FIG. 1, the hand cart 12 while it is mounted on the dolly 10 may be swung through an arc, about a horizontal axis which is defined by the horizontal cross bar 31 of the hand cart.

Further construction of the hand cart involves the provision of a foot brake, comprising a pair of levers 58 which are pivotally secured to the side members 30 of the hand cart and also pivoted to each other, said levers having side extensions 59 adapted to engage the wheels 37 of the hand cart, to prevent rotation of such wheels. The levers 58 have a toggle action whereby they will be retained in either a released position as shown in FIGS. 2 and 4 or else a braking or locking position wherein the portions

59 engage the wheels 37, as will be readily understood in the art.

Where it may be desired to mount the outboard engine 42 in a different position, particularly where such engine is one of the larger sizes, we further provide an optionally usable side mounting member 60, FIG. 6, which may be of construction similar to the mounting brace 39, having a rectangular cross-section. The side mounting member 60 may be provided with a pair of strips 62 secured to its upper and lower surfaces adjoining one end, said strips being threaded at their ends and adapted to extend past opposite top and bottom edges of the cross bar 39 and through a clamping plate 64 where, by means of nuts 65 threaded on the strips 62 the clamping plate may be pulled up tightly against the back of the cross bar 39, thereby to rigidly mount the side support 60 on the cross bar. By this construction an outboard engine may be mounted on and fastened to the side bar 60, where the shape or configuration of the engine lends itself more readily to this type of mounting.

The operation of our improved engine carrier and handling device is as follows:

Considering that the outboard engine 42 is resting on the ground, the hand cart 12 is removed from the dolly 10 and brought to the engine. The engine is placed on its side and the hand cart also positioned on its side, to enable the engine brackets to be engaged with the cross bar 39 of the hand cart, and secured thereto. The depending drive shaft and propeller portion of the engine will then extend somewhat parallel to the side rails or members 30 of the hand cart, as indicated by one dotted outline shown in FIG. 1.

After the outboard engine has been securely fastened to the hand cart, it is now a simple matter to turn the hand cart from its side, so that both wheels 37 thereof rest on the ground, and also the handles 33. The operator now grasps the handles 33 and raises the hand cart, this operation being facilitated by virtue of the mechanical advantage provided by the long side members 30, together with the mounting of the engine at points intermediate the tops and bottoms of the side members. With the hand cart 12 in its upright position as just described, the cart may be readily transported from the dock or boat to any desired point, as for example to a vehicle which is waiting.

At this point, the dolly 10 is employed, in order that the engine may be readily lifted and placed in the vehicle. For this operation the hand cart is held in its upright position, and the dolly 10 is brought to the rear of the hand cart and tilted by raising the free end of the center bar 14 in order to position the cross member 52 of the dolly under the cross brace 31 of the hand cart. These parts are thus engaged with each other while the dolly is still tilted, whereupon the operator places his foot upon the center bar 14 and applies downward pressure. Because of the advantageous leverage and the ease of applying pressure with the foot, the dolly 10 may now be righted, thereby lifting the hand cart 12 from the ground, together with the outboard engine carried by the hand cart. The position of the cart will now be approximately as shown by that broken outline in FIG. 1 which locates the cart wheels to the left of the part 22 and the cart handles to the right. The cart is now swung through a 180° arc about the axis of the part 22.

After this has been done the approximate position of the hand cart will be similar to that shown by the broken horizontal outline in FIG. 1, with the dolly 10 now in its upright position. The operator still grasping the handles 33 now tilts the cart 12 to the upright position shown in FIG. 1 in full lines, engaging the shaft 35 with the spring clip 56, and may then shift the dolly 10 to a position adjoining the tailboard or trunk or other receptacle of the vehicle. This may be easily done because of the large wheels 16 on the dolly, together with the large caster 18 which enables the dolly to be readily

maneuvered. When as in this instance the hand cart carrying the engine and the dolly 10 are to be moved while all assembled together the spring clip 56 which engages the shaft 35 of the hand cart has great utility in stabilizing the mounting of the hand cart on the dolly, as will be readily understood. The operator now tilts the hand cart to a position almost horizontal as shown in broken outlines in FIG. 1, together with the corresponding position of the outboard engine 42 shown in broken outline.

10 The assemblage of hand cart and engine may now be swung horizontally, about an upright axis as defined by the upright post 21 of the dolly. Thus, the wheels 37 of the hand cart, being raised appreciably off the ground, may now be brought level with the tailboard of the vehicle or the floor of the trunk compartment of the like. The hand cart is maneuvered to completely place the wheels 37 thereof upon the said floor portion of the vehicle, whereupon the operator lifts upward on the handles 33 thereby raising the hand cart from the dolly 10 and 15 disengaging the separable connection constituted by the cross bar 31 of the hand cart and the cross member 52 of the dolly.

20 The operator may now wheel the hand cart and engine carried thereby into the vehicle to the desired position. 25 In most instances, the trunk compartments of vehicles will be sufficiently large to completely contain the outboard engine with the hand cart assembled to it. The operator may now dismantle the dolly by removing the upper post portion 22, as indicated in FIGURE 5, whereupon the two parts of the dolly may be stored in the vehicle.

30 It will be readily appreciated from the foregoing description that the operator need not at any time employ direct lifting, in positioning the outboard engine where desired. In all instances the operator is aided by the mechanical advantage afforded through the medium of the hand trunk 12 and the dolly 10.

35 The operation of removing the outboard engine from the vehicle and transporting it to any desired point follows a reverse sequence to that described above. The dolly is first assembled on the ground, and then the hand cart is pulled from the trunk compartment or trunk body and positioned on the hand cart, whereupon the cart and engine are swung horizontally clear of the vehicle.

40 45 When the hand cart is in the clear with the engine, the dolly 10 may be permitted to tilt, whereupon the wheels of the hand cart will be brought to the ground, enabling the dolly to be now completely removed. Thereafter, the hand cart may be wheeled to the desired location and then placed on one side, and the outboard engine disconnected and dismounted from the hand cart.

50 55 It will be readily understood that in accordance with the foregoing we have provided an extremely simple, yet sturdy and effective means by which an outboard engine may be conveniently handled and transported even by a person of limited strength and skill. The construction of the hand cart 12 and dolly 10 involves relatively few components, and the entire carrier may thus be economically fabricated and produced.

60 65 Moreover, by virtue of the sturdiness of the parts involved there is no likelihood of failure which might result in damage or injury to the operator.

Variations and modifications may be made within the scope of the claims, and portions of the improvements 65 may be used without others.

We claim:

1. A one-man operable outboard engine carrier comprising in combination a dolly having a horizontal frame and means for supporting said frame on the ground in a stable horizontal position while permitting travel of the frame over the ground; a hand cart having wheels at its lower end and a handle at its upper end, and having support means intermediate said ends on which an outboard marine engine may be mounted and to which it may be secured; means mounting said hand cart on the dolly

wholly out of contact with the ground, said means providing for pivotal movement of the cart between substantially vertical and horizontal positions about a horizontal axis located intermediate the upper and lower ends of the hand cart and for swinging movement of the hand cart about a vertical axis with respect to the said horizontal frame and while said frame remains stationary, said cart having a frame which is disposed wholly above the horizontal frame of the dolly when the cart is in vertical position, said means including a separable connection enabling the cart to be wholly removed from the dolly for transportation of the engine over the ground independently of the dolly.

2. A one-man operable outboard engine carrier comprising in combination a dolly having a horizontal frame and means for supporting said frame on the ground in a stable horizontal position while permitting travel of the frame over the ground; a hand cart having wheels at its lower end and a handle at its upper end, and having support means intermediate said ends on which an outboard marine engine may be mounted and to which it may be secured; means mounting said hand cart in vertical position on the dolly wholly out of contact with the ground, said means providing for swinging movement about a vertical axis, said cart having a frame which is disposed wholly above the horizontal frame of the dolly when the cart is in vertical position, and said means including a separable connection enabling the cart to be wholly removed from the dolly for transportation of the engine over the ground independently of the dolly.

3. A one-man operable outboard engine carrier comprising in combination a dolly having a horizontal frame and means for supporting said frame on the ground in a stable horizontal position while permitting travel of the frame over the ground; a hand cart having wheels at its lower end and a handle at its upper end and having support means intermediate said ends on which an outboard marine engine may be mounted and to which it may be secured; means mounting said hand cart on the dolly wholly out of contact with the ground, said means providing for swinging movement between horizontal and vertical positions about a horizontal axis and for swinging movement about a vertical axis with respect to the said horizontal frame and while said frame remains stationary, said cart having a frame which is disposed wholly above the horizontal frame of the dolly when the cart is in vertical position, said means including a separable connection enabling the cart to be wholly removed from the dolly for transportation of the engine over the ground independently of the dolly, the said mounting means comprising an upright multi-part post permanently carried on the dolly, said post having a pair of separable telescoping sections and said sections having cooperable abutting shoulders positioning them axially with respect to each other.

4. A one-man operable outboard engine carrier comprising in combination a dolly having a horizontal frame and means for supporting said frame on the ground in a stable horizontal position, while permitting travel of the frame over the ground; a hand cart having wheels at its lower end and a handle at its upper end and having support means intermediate said ends on which an outboard marine engine may be mounted and to which it may be secured; means mounting said hand cart on the dolly wholly out of contact with the ground, said means providing for pivotal movement of the cart between substantially vertical and horizontal positions about a horizontal axis located intermediate the upper and lower ends of the hand cart and for swinging movement of the hand cart about a vertical axis with respect to the said horizontal frame and while said frame remains stationary, said cart having a frame which is disposed wholly above the horizontal frame of the dolly when the cart is in vertical position, said means including a separable connection enabling the cart to be wholly removed from the dolly for

transportation of the engine over the ground, independently of the dolly, the said frame of the dolly comprising a T-shaped structure having a stem and having at one end of the stem a cross bar, said dolly including wheels 5 rotatably mounted at the ends of the cross bar, and including a caster mounted at the free end of the stem.

5. A one-man operable outboard engine carrier comprising in combination a dolly having a horizontal frame and means for supporting said frame on the ground in a stable horizontal position, while permitting travel of the frame over the ground; a hand cart having wheels at its lower end and a handle at its upper end and having support means intermediate said ends on which an outboard marine engine may be mounted and to which it may be secured; means mounting said hand cart on the dolly wholly out of contact with the ground, said means providing for pivotal movement of the cart between substantially vertical and horizontal positions about a horizontal axis located intermediate the upper and lower ends of the hand cart and for swinging movement of the hand cart about a vertical axis with respect to the said horizontal frame and while said frame remains stationary, said cart having a frame which is disposed wholly above the horizontal frame of the dolly when the cart is in vertical position, said means including a separable connection 10 enabling the cart to be wholly removed from the dolly for transportation of the engine over the ground independently of the dolly, said mounting means comprising an upright post carried by the dolly and having a pair of relatively turnable telescoping sections and further comprising cooperable shoulder means on the hand car and the upper extremity of the post, the shoulder means on the post being constituted of a channel member extending horizontally and adapted to nest the shoulder means on the hand cart.

6. A one-man operable outboard engine carrier comprising in combination a dolly having a horizontal frame and means for supporting said frame on the ground in a stable horizontal position, while permitting travel of the frame over the ground; a hand cart having wheels at its lower end and a handle at its upper end and having support means intermediate said ends on which an outboard marine engine may be mounted and to which it may be secured; means mounting said hand cart on the dolly wholly out of contact with the ground, said means providing for pivotal movement of the cart between substantially vertical and horizontal positions about a horizontal axis located intermediate the upper and lower ends of the hand cart and for swinging movement of the hand cart about a vertical axis with respect to the said horizontal frame and while said frame remains stationary, said cart having a frame which is disposed wholly above the horizontal frame of the dolly when the cart is in vertical position, said means including a separable connection 15 enabling the cart to be wholly removed from the dolly for transportation of the engine over the ground independently of the dolly; and means on the said dolly and lower portion of the hand cart, for releasably holding the said lower portion in a predetermined operative position of the dolly.

7. A one-man operable outboard engine carrier comprising in combination a dolly having a horizontal frame and means for supporting said frame on the ground in a stable horizontal position, while permitting travel of the frame over the ground; a hand cart having wheels at its lower end and a handle at its upper end and having support means intermediate said ends on which an outboard marine engine may be mounted and to which it may be secured; means mounting said hand cart on the dolly wholly out of contact with the ground, said means providing for pivotal movement of the cart between substantially vertical and horizontal positions about a horizontal axis located intermediate the upper and lower ends of the hand cart and for swinging movement of the hand cart 20 about a vertical axis with respect to the said horizontal

frame and while said frame remains stationary, said cart having a frame which is disposed wholly above the horizontal frame of the dolly when the cart is in vertical position, said means including a separable connection enabling the cart to be wholly removed from the dolly for transportation of the engine over the ground independently of the dolly, said frame of the dolly having a T-shaped structure comprising a stem and a cross bar secured to one end of the stem and having wheels rotatably mounted on the ends of the cross bar, said cross bar having a width greater than the width of the hand cart and said stem having a length at least as great as the length of said cross bar.
